UNITED STATES PATENT OFFICE.

WILLIAM B. PROUTY, OF RIDGWAY, PENNSYLVANIA.

DESIGN FOR A CLIP-BLANK FOR CANT-HOOKS.

SPECIFICATION forming part of Design No. 29,518, dated October 18, 1898.

Application filed September 19, 1898. Serial No. 691,383. Term of patent 14 years.

To all whom it may concern:

Be it known that I, WILLIAM B. PROUTY, a citizen of the United States, residing at Ridgway, in the county of Elk and State of Pennsylvania, have invented and produced a new and original Design for a Clip-Blank for Cant-hooks, of which the following is a specification.

This invention relates to a new and original design for a clip-blank for cant-hooks; and it has for its object to provide a design of his character that shall be both useful and ornamental.

The leading or essential feature of the design resides in a clip-blank having an approximately rectangular body-plate provided at its side extremities with thickened squared ear portions having openings therein and provided below the plane of such openings with laterally-offset triangular lug projections, said body-plate being further provided at its top edge and centrally between the squared ear portions thereof with a rounded up-standing lip.

While the distinctive features of the design sought to be covered have been pointed out, the minor features of the design may be stated to be the ear portions of the body-plate having inclined edges forming one of the faces of the triangular lug projections and the body-plate provided below the plane of said lug projections with an apron extension having obtuse-angled side edges and V-shaped points at its upper corners.

In the accompanying drawings, Figure 1 is a perspective view of a clip-blank for cant-hooks embodying the herein-described design. Fig. 2 is a plan view or elevation hereof.

Referring to the accompanying drawings, 40 the numeral 1 designates the body-plate of an approximately-rectangular outline and provided at its opposite side extremities with thickened squared ear portions 2, having circular openings 3 therein and provided below 45 the plane of such openings with laterally-offset triangular lug projections 4. The said squared ear portions 3 are further provided with inclined faces 5, forming one of the faces of the triangular lug projections 4, and 50 at their upper inner corners with the laterally-projecting bosses 6.

The body-plate has the top edge thereof sigmoidally curved into the ear portions 2 and is provided at such edge and centrally 55 between the ear portions with a rounded up-standing lip 7.

The body-plate 1, in addition to the features already described, is further provided below the plane of the lug projections 4 with a socket-forming apron extension 8. This apron extension 8 forms a continuation of the main upper portion of the body-plate and is provided with obtuse-angled side edges 9 and at its upper corners, at one side of the lug projections 4, with V-shaped points 10.

What is claimed is—

The design for a clip-blank for cant-hooks, herein shown and described.

In testimony that I claim the foregoing as 70 my own I have hereto affixed my signature in the presence of two witnesses.

W. B. PROUTY.
